UNITED STATES PATENT OFFICE.

GEORGE E. KRICKER, OF CLEVELAND, OHIO, ASSIGNOR TO THE STANDARD PARTS COMPANY, OF CLEVELAND, OHIO, A CORPORATION OF OHIO.

RIM.

1,408,893.

Specification of Letters Patent.

Patented Mar. 7, 1922.

Application filed August 2, 1919. Serial No. 314,876.

To all whom it may concern:

Be it known that I, GEORGE E. KRICKER, a citizen of the United States, and a resident of Cleveland, county of Cuyahoga, 5 State of Ohio, have invented certain new and useful Improvements in Rims, of which the following is a specification.

This invention relates to rims, and more particularly to vehicle wheel rims of the 10 "quick-detachable" type provided with a circumferential groove adjacent one edge and adapted to receive a side ring which is detachable from the rim, to facilitate removal or replacement of a tire.

15 One of the objects of the invention is to provide simple and effective means for securing the detachable side ring in position on the rim.

Other objects of the invention and the 20 features of novelty will be apparent from the following description, taken in connection with the accompanying drawings, in which:—

Figure 1 is a fragmentary side elevation 25 of a vehicle wheel rim embodying my invention, certain of the parts being broken away, to more clearly disclose the structure;

Fig. 2 is a bottom plan view of the structure shown in Fig. 1;

Fig. 3 is a fragmentary cross-section on the line 3—3 of Fig. 1;

Fig. 4 is a fragmentary side elevation, similar to Fig. 1, but showing a modified structure embodying my invention;

Fig. 5 is a bottom plan view of the structure shown in Fig. 4;

Fig. 6 is a fragmentary view in perspective of the rim shown in Figs. 4 and 5, with the side ring removed;

Fig. 7 is a fragmentary vertical section on the line 7—7 of Fig. 4;

Figs. 8, 9 and 10 are fragmentary side elevations, similar to Fig. 1, showing further modified structures embodying my invention;

Fig. 11 is a bottom plan view of the structure shown in Fig. 10; and

Fig. 12 is a fragmentary cross-section on the line 12—12 of Fig. 10.

Throughout the drawings, I have indicated at 11 a vehicle wheel rim having a

tire-securing flange 12 at one edge, and provided adjacent its other edge with a circumferential channel or groove 13, to receive a detachable side ring 14 which is 55 transversely split, as shown at 15, and has a base or web portion 16 thereon which extends inwardly therefrom and is adapted to be seated in the groove 13, the side ring being sufficiently resilient to permit the web 60 portion 16 to be lifted over the outer side wall 17 of the groove 13. Adjacent each end, the side ring 14 is provided with an inwardly extending lug, such lugs being adapted to project through the rim at the 65 bottom of the groove 13 and to be held in such seated position, thereby preventing expansion of the side ring 14 and securing it in position upon the rim 11.

In the structure shown in Figs. 1 to 3, 70 the lugs 18 and 19 on the ends of the side ring extend through apertures 20 and 21 in the rim, such apertures being separated by a web portion 22 upon which the ends of the side ring seat and which, by engagement 75 with the lugs, assists in securing the side ring from circumferential motion on the rim. Each of the lugs 18 and 19 is provided with a latch member 23 pivotally secured thereon, the lugs being provided with studs 24 which 80 project through the latch members 23 and are riveted over, at their inner ends, to secure such members in place. One end of each of the members 23 is formed with an inclined face 25, for a purpose which will 85 be later described, and the length of the members is greater than the width of the apertures 20 and 21 so that, while such members are adapted, in one position, to pass through the apertures, they may be turned 90 to a transverse position, as shown in Fig. 3, in which they will engage the under side of the rim, to hold the lugs in seated position.

It will be understood that in seating the side ring upon the rim, one of the ends is 95 first seated with its lug, 18 or 19, in its aperture, 20 or 21, and locked therein, by turning the latch member 23 to the transverse position shown in Fig. 3, the side ring being then circumferentially seated around the 100 rim by lifting the web portion 16 over the side wall 17 of the groove until the lug at

the other end of the ring registers with its aperture. If the lug last seated does not accurately register with its aperture, the inclined face 25 of the member 23 on the lug 5 will facilitate the entry of the lug in its aperture, when radially inward pressure is applied to the side ring, by reason of the engagement of such inclined surface with the rim at the edge of the aperture.

10 In the structure shown in Figs. 4 to 7, the lug 26 at one end of the side ring is formed with a rearwardly extending toe 27 which is adapted to hook under the rim and engage the under side thereof to hold 15 the end of the side ring from moving radially outward, it being necessary, in placing the side ring on the rim, to seat this end of the rim first, and move it slightly in a circumferential direction to the position 20 shown in Figs. 4 and 5. The lug 28 on the other end of the side ring is provided with a latch member 29 pivotally secured thereto and adapted, in one position, to pass through the opening 30 in the rim. An in- 25 wardly projecting flange 31 is formed on the rim and is provided with a slot 32 therein, the latch member 29 being movable to a transverse position, as shown in Figs. 5 and 7, in which it engages in such slot 32, 30 to secure the ring in seated position. The flange 31 may be conveniently formed from the metal of the rim, by shearing the rim through at the bottom of the groove 13 and bending the flange outwardly, as shown in 35 Fig. 6, and, while it is unnecessary to provide a flange of this kind, inasmuch as the latch member 29 could interlock with the bottom of the rim, it will be understood that the flange will assist in holding the member 40 29 in its ring-securing position and will protect the member from accidental displacement.

In Figs. 8 and 9, I have shown a lug 33 on one end of the side ring 14 as provided 45 with a latch member 34 pivotally secured thereon and adapted to interlock with the lug at the other end of the side ring. The latch member 34 may be pivotally secured on a stud which extends inwardly from the 50 lug and is riveted over, as shown at 35, to hold the member in position, or the lug may be cut away, as shown at 36 in Fig. 9, and the member 34 pivotally secured thereon, as by a rivet 37. The latch member 34 is 55 formed with an up-turned tongue 38 at its end, and the lug 39 at the other end of the side ring is provided with a transverse opening 40 which is adapted to receive the end of the member 34, when such member is 60 turned to the full-line position shown in Figs. 8 and 9. A slight projection 41 may be formed on the latch member 34 to engage in an opening 42 in the lug, to hold the member in ring-securing position and 65 the lugs are preferably provided with in-

clined rear faces, as shown at 43, to facilitate the entry of the lugs into the aperture in the rim.

In the structure shown in Figs. 10 to 12, the lugs 44 and 45 on the ends of the side 70 ring are adapted to be seated in separate apertures 46 and 47 in the rim, which are separated by a web portion 48. A latch member 49 is pivotally secured, as by a rivet 50, to the lug 45, the lug being formed with 75 a lateral recess 51 to receive the member 49 so that the latch member, when in one position, will pass through the aperture 47. The lug 44 on the other end of the ring is provided with a similar recess 52 which is 80 adapted to receive the other end of the member 49 when such member is swung to the position shown in Fig. 10. The latch member 49 is preferably provided with a projection 53 thereon which is adapted to engage 85 with a recess 54 in the lug 44, as best illustrated in Fig. 12, to hold the member in ring-securing position, and a slot 55 is preferably formed in the latch member 49 to receive an operating tool and facilitate its 90 movement to or from locking position. The lugs 44 and 45 are preferably provided with inclined rear faces 56 to facilitate the entry of the lugs in their apertures. When the 95 side ring has been seated on the rim and the latch member 49 moved to the position shown in Fig. 10, it will be understood that radially outward movement of the ends of the ring will be prevented by the engagement of the latch member with the web portion 48, and the side ring will thus be secured in seated position.

Having thus described my invention, what I claim is:

1. In a vehicle wheel of the class de- 105 scribed, the combination of a tire-carrying rim having an opening therein, a split side ring detachably seated on said rim, and means for securing said side ring on said rim comprising a lug on said ring adjacent 110 its end and extending radially through said rim, and a latch member rotatably carried by said lug and adapted in one position to pass through said opening.

2. In a vehicle wheel of the class de- 115 scribed, the combination of a tire-carrying rim having an opening therein, a split side ring detachably seated on said rim, and means for securing said side ring in seated 120 position, comprising lugs on said ring adjacent its ends, and a latch member carried by one of said lugs and adapted in one position to pass through said opening and in another position to engage the other lug.

3. In a vehicle wheel of the class de- 125 scribed, the combination of a tire-carrying rim, a split side ring detachably seated on said rim, lugs on said side ring adjacent its ends, a latch member pivoted to one of said lugs and adapted to engage the other of 130

said lugs to secure said side ring in seated position, and means for holding said latch member in ring-securing position.

4. In a vehicle wheel of the class described, the combination of a tire-carrying rim, having a pair of openings therein separated by a web, a split side ring detachably seated on said rim, lugs on said side ring

adjacent its ends and extending through said openings, and a latch pivotally secured to one of said lugs and cooperating with said lugs and said web to secure said side ring in seated position.

In testimony whereof I affix my signature.

GEORGE E. KRICKER.
